SANDAL

John F. Feeks, Los Angeles, Calif.

Application June 21, 1952, Serial No. 20,306

Term of patent 14 years

(Cl. D7—7)

To all whom it may concern:

Be it known that I, John F. Feeks, a citizen of the United States, residing at Los Angeles, in the county of Los Angeles and State of California, have invented a new, original, and ornamental Design for a Sandal, of which the following is a specification, reference being had to the accompanying drawing, forming part thereof.

Figure 1 is a view in perspective as viewed from the front and right side of a sandal embodying my new design; and

I claim:

The ornamental design for a sandal, substantially as shown.

JOHN F. FEEKS.
